UNITED STATES PATENT OFFICE.

WILLIAM I. STILWELL, OF CLEVELAND, OHIO.

DESIGN FOR A ROLLER-CASTER SOCKET.

SPECIFICATION forming part of Design No. 28,323, dated March 1, 1898.

Application filed November 18, 1897. Serial No. 658,762. Term of patent 7 years.

To all whom it may concern:

Be it known that I, WILLIAM I. STILWELL, a citizen of the United States, and a resident of Cleveland, county of Cuyahoga, State of Ohio, have invented certain new and useful Improvements in Designs for Roller-Caster Sockets, of which I hereby declare the following to be a full, clear, and exact description, such as will enable others skilled in the art to which it appertains to make and use the same, reference being had to the accompanying drawings, forming part thereof.

In the accompanying drawings, Figure 1 is a bottom and Fig. 2 a top view of my design. Fig. 3 is a side view, and Fig. 4 is a vertical central section. These views are deemed essential to fully illustrate the design.

The leading feature of my design consists of a cup-shaped socket-body 1, provided with tapering circular sides 2 on the interior and vertical sides 3 on the exterior surfaces. An annular recess is sunk at 4 in the exterior horizontal surface formed at the closed extremity of the socket, and a tapering screw-

shaped projection 5 extends vertically from the center of the horizontal surface. Curved lines join the exterior and interior surfaces of the socket at 6, presenting a sharp edge at the juncture with the interior surface at 7. In the interior of the socket raised projections 8, placed at the angular juncture of the inner horizontal plane and vertical inner sides, are provided with semiglobular cavities 9, the upper faces of the projections being cut away at 10 at an angle of forty-five degrees. A hexagonal shape is given the outer surface of the closed extremity of the socket at 11, the width of which is about one-seventh of the height of the socket.

What I claim as my invention, and desire to secure by Letters Patent, is—

The design for a roller-caster socket substantially as herein shown and described.

WILLIAM I. STILWELL.
